[57]**CLAIM**

The ornamental design for a fluid dispenser housing, as shown and described.

DESCRIPTION

FIG. 1 is a top, front, and right side perspective view of a fluid dispenser housing showing our new design, the broken-line disclosure of a portion of a wall being for illustrative purposes only and forming no part of the claimed design;

FIG. 2 is a front elevational view thereof;

FIG. 3 is a top plan view thereof;

FIG. 4 is a rear elevational view thereof;

FIG. 5 is a left side elevational view thereof, the right side being a mirror image of that shown; and,

FIG. 6 is a bottom plan view thereof.

FIG. 1

FIG. 2

FIG. 3

FIG. 4

FIG. 5

FIG. 6
